DESIGN FOR A ROOF OR THE LIKE

Thomas William Foley, New Haven, Conn.

Application December 20, 1937, Serial No. 73,766

Term of patent 14 years

To all whom it may concern:

Be it known that I, Thomas William Foley, residing at 1285 Boulevard, New Haven, in the county of New Haven and State of Connecticut, have invented a new, original, and ornamental Design for a Roof or the Like, of which the following is a specification, reference being had to the accompanying drawing, forming part thereof.

Fig. 1 is a plan view of a section of a roof showing my new design; and

Fig. 2 is a detailed plan view of the shingle element which forms the roof.

I claim:

The ornamental design for a roof or the like as shown and described.

THOMAS WILLIAM FOLEY.
